ELECTRIC SWITCH

William George Bourne, London, England, assignor to Rotax Limited, London, England

Application May 5, 1948, Serial No. 25,192
In Great Britain May 8, 1947

2 Claims. (Cl. 200—68)

1

This invention relates to electric switches of the tumbler type. These switches are known in many different forms, and are adapted to operate in a number of different ways, all depending on the actuation of a pivoted finger lever. In some switches the movement of the finger lever from one limiting position to another serves to open or close a single electric circuit, or to open one circuit and close another. Or, with the lever normally occupying a central position, control of either of two circuits is effected by moving the lever to one side or the other of the said position. Moreover, in some switches the lever is held by the action of a spring in the position to which it has been moved, in others it is automatically returned by a spring to its initial position when the finger lever is released. Hitherto the provision of a range of switches individually capable of operating in any of the above-mentioned or other analogous ways, has involved much multiplication of component parts and consequent complication of manufacturing operations. An obviously desirable condition from consideration of economy of manufacture is that all the switches in a given range should employ as many similar components as possible, and the object of the present invention is to enable this condition to be met in a convenient and satisfactory manner.

In the accompanying drawings,

Figure 1 is a side sectional elevation of an electric switch of the tumbler type constructed in accordance with the invention and arranged for the control of either of two circuits by moving the finger lever to one side or the other of a central or neutral position;

Figure 2 is an end sectional elevation of the switch taken on the centre line of Figure 1;

Figure 3 is a side elevation of a part of the switch mounting and rocker, with the cam piece omitted;

Figure 4 is an elevation, partly in section, of a portion of the switch mechanism of Figure 1, provided with a modified form of cam piece;

Figure 5 is a view similar to Figure 4 showing another modified form of cam piece;

Figure 6 is a view similar to Figure 5 showing a further modified form of cam piece.

In carrying the invention into effect according to one convenient mode as illustrated in Figures 1, 2 and 3, there is provided a sheet metal mounting 1 for carrying the finger lever and rocker of the switch. The mounting is of deep U-section having a pair of parallel sides which are wider at their upper ends, and which at their lower ends are joined by an integral cross part 2. At about

the mid point of each of the sides there is formed an aperture 3.

The rocker is a sheet metal part having a pair of arms 4 extending in opposite directions from its central portion, the outer end of each arm serving as or having secured to it a contact piece 5. The central part 6 of the rocker is also of U-section and the upper ends of its sides are bent over at 7 (or are provided with pins) to engage the apertures 3 in the mounting 1 and serve as pivotal connections between the rocker and mounting, the rocker being located between the sides of the mounting as shown in Figure 2.

The finger lever may be of any convenient construction. Preferably it consists in part of a metal stem 8 which has a cylindrical bore 9 extending for a convenient distance from its inner end, and in this bore is accommodated a helical spring 10 which bears on a metal ball 11 inserted in the lower end of the bore, the ball serving as the abutment required to co-operate with the cam piece to be hereinafter described. This metal stem is encased from about its centre to its outer end by a sheath 12 of thermoplastic or analogous material, and the inner end of the sheath has moulded on it a spherical part 13 adapted to occupy a corresponding seating 14 in a cover piece 15. The cover piece is provided also with a slot 16 through which the outer end of the lever 8 extends. The central and inner parts of the lever lie between the sides of the mounting 1, and the central part is connected to the mounting by a pair of coaxial pivot pieces 17. The mounting 1 is secured to the cover 15 by screws 18.

On the rocker is mounted a separately made cam piece 19, and it is the form of this piece that determines the mode of action of the switch. The combination of mounting, finger lever and rocker, serves for any switch in the range to be manufactured, the only component which is different for different switches being the cam piece. If it is required to provide a switch of the kind in which the finger lever occupies a midposition when the switch is open, and in which movement of the lever to either side of this position serves to close one or the other of a pair of circuits to be controlled by the switch, the cam piece consists of a flat metal piece as shown in Figures 1 and 2 having at the centre of its upper edge a recess 20 adapted to be engaged by the spring loaded ball 11 above mentioned on the finger lever 8, and having at the opposite sides of the recess a pair of similar and upwardly inclined straight edges 21 on which the ball can act when the finger lever 8 is moved. The under edges 22 of the cam piece

are adapted to seat firmly on the upper surfaces of the arms 4 of the rocker, and preferably it is provided with a central projection 23 which occupies a recess between the said arms, the cam piece being secured to the rocker by a rivet, cotter or the like 24 inserted through it and through the sides of the rocker 6. This cam piece is such that with movement of the finger lever to either side of its central position the rocker is caused to move about its pivotal connection with the mounting under the action of the spring loaded ball 11 on one of the inclined edges 21 of the cam piece, and these edges are so designed that the rocker and the finger lever will be moved automatically to circuit opening position as soon as the finger lever is released, the rocker then being held by the engagement of the ball with the recess 20 in the cam piece.

As regards the remainder of the switch this may take a variety of forms. In the example illustrated there is provided an insulating base 25 carrying a pair of contacts 26 for co-operating with the rocker contacts 5. The base may be secured to the mounting 1 by a screw but preferably and as shown a metal member 27 is moulded into the base and has a cylindrical part 28 which is riveted over a hole in the cross part 2 of the mounting. The cover piece 15 is extended to form a wall 29 which encloses the base, and to the lower end of this wall a second cover piece 30 is secured by a screw 31 to enclose the under side of the base and the terminal connections provided on the base.

It will be seen that with the arrangement described the finger lever may occupy a middle or neutral position, or may be moved to one side or the other to close either of two circuits, and will return automatically to said middle or neutral position as soon as positive pressure on the finger lever is removed.

If it is required to provide a two way switch such that one of a pair of circuits to be controlled is closed when the other is open, the cam piece described in the previous example is replaced by a different cam piece as shown in Figure 4. The cam piece 32 for this purpose is similar to the previously described cam piece 19 except for the shape of its upper edge which has at its centre an inverted V-ridge 33 and a straight edge 34 which is given a slight upward inclination at either side of the V-ridge. With this cam piece in position the finger lever can only rest in one or other of its inclined positions as shown in Figure 4, i. e. one or other of the circuits controlled by the contacts 26 will always be closed. The construction of the remainder of the switch is the same as described for the previous example.

For some purposes it is required that the finger lever shall occupy a central position when the switch is open, and that when moved in one direction from that position it shall close one of a pair of associated circuits, this circuit remaining closed until opened by positive movement of the finger lever in the reverse direction, but as regards the other circuit it is required that when closed it can remain closed only so long as the user exerts pressure on the finger lever. This requirement is met by the use of a modified form of cam piece as shown in Figure 5. The cam piece 35 is similar so far as one half of it is concerned to the cam piece of Figures 1 to 3. Thus there is provided a central depression 36 and on one side of it an inclined surface 37 arranged so that when depressed by the ball 11 of the finger lever the latter will remain in position with the contacts closed only so long as positive pressure

is exerted on the finger lever, the finger lever and rocker returning automatically to circuit opening position as soon as such pressure is removed. On the other side of the depression 36 there is provided a gently inclined surface 38 (similar to the inclined surfaces 34 shown in Figure 4) so disposed that its interaction with the spring loaded ball 11 causes the finger lever and rocker to remain in position with the contacts closed until released by positive actuation. The construction of the remainder of the switch is the same as described in connection with Figures 1 to 3.

For other purposes it is required that the switch shall remain in circuit closing position when the finger lever is moved to either side of the central position. This requirement is met by the use of the modified form of cam piece shown in Figure 6. The cam piece 39 is similar to the previously described cam pieces except for the shape of the upper surface thereof. There is provided a central depression 40 and a pair of gently inclined surfaces 41 on either side thereof, these being disposed in a similar manner to the surface 38 of the previously described example. The operation of the switch will be clear from the foregoing description.

From the foregoing it will be seen that any of a variety of requirements can be met by the use of an appropriately shaped cam piece, and it is to be understood that the invention is not limited to the examples specified. Further whilst in the foregoing there has been described the application of the invention to double acting switches, it will be understood that the same components may be used in single acting switches, the rocker being then provided with a contact at one end only.

By this invention the manufacture of a range of different tumbler switches can be greatly simplified, as most of the components are the same for all the switches in the range, the only (or principal) component which is different in the different switches and which determines the action of the switch being the cam piece.

The invention is not, however, restricted to the particular construction of mounting, finger lever, rocker and cover piece above described, as these and other features may be modified to suit different requirements.

Having thus described my invention what I claim as new and desire to secure by Letters Patent is:

1. An electric switch having in combination a base piece, at least one fixed contact on said base piece, a cover piece, a mounting of deep U-form secured at its open end to said cover piece at its closed end to said base piece, a finger lever extending through an aperture in said cover piece and carried by said mounting, a movable contact piece in the form of a rocker also carried by said mounting and arranged to co-operate with said fixed contact, a cam piece made separately from and rigidly secured to said rocker so as to be movable therewith but incapable of movement relatively thereto, and a spring loaded abutment piece slidably supported by the inner end of said finger lever and arranged in contact with said cam piece so that movement of said finger lever is accompanied by movement of said cam piece and rocker.

2. An electric switch as claimed in claim 1, in which said rocker comprises a pair of contact arms extending in opposite directions from and formed integrally with a central U-shaped part which at its upper ends is provided with lateral
